Primary Examiner — Khawaja Anwar*Assistant Examiner* — Taylor O Mortorff(74) *Attorney, Agent, or Firm* — Shumaker, Loop & Kendrick, LLP(57) **CLAIM**

The ornamental design for a golf glove drying device, as shown and described.

DESCRIPTION

FIG. 1 is a front perspective view of the golf glove drying device;

FIG. 2 is a back perspective view thereof;

FIG. 3 is a back view thereof;

FIG. 4 is a right side view thereof;

FIG. 5 is a left side view thereof;

FIG. 6 is a top view thereof;

FIG. 7 is a front view thereof; and,

FIG. 8 is a bottom view thereof.

Longer broken lines represent stitching. The shorter broken lines represent portions of the golf glove drying device that form no part of the claimed design.

1 Claim, 4 Drawing Sheets(56)
